(57) **CLAIM**

The ornamental design for a water cooler with retractable legs, as shown and described.

DESCRIPTION

FIG. 1 is a top front perspective view of a water cooler with retractable legs showing our new design with the legs deployed;

FIG. 2 is a top plan view thereof;

FIG. 3 is a front elevational view thereof;

FIG. 4 is a right side elevational view thereof;

FIG. 5 is a rear plan view thereof;

FIG. 6 is a bottom isometric view thereof;

FIG. 7 is a left side elevational view thereof;

FIG. 8 is an enlarged top front perspective view of a water cooler with retractable legs with the legs retracted;

FIG. 9 is an enlarged bottom perspective view thereof;

FIG. 10 is an enlarged top perspective view thereof;

FIG. 11 is an enlarged rear view thereof; and,

FIG. 12 is an enlarged top plan view thereof.
